UNITED STATES PATENT OFFICE

168,814

POPCORN MACHINE

Samuel M. Waas, Kansas City, Mo., assignor to Manley, Inc., Kansas City, Mo., a corporation of Missouri

Application January 14, 1952, Serial No. 18,051

Term of patent 14 years

(Cl. D81—10)

To all whom it may concern:

Be it known that I, Samuel M. Waas, a citizen of the United States, residing at Kansas City, in the county of Jackson and State of Missouri, have invented a new, original, and ornamental Design for a Popcorn Machine, of which the following is a specification, reference being had to the accompanying drawing forming a part thereof, wherein:

I claim:

The ornamental design for a popcorn machine, as shown.

SAMUEL M. WAAS.
